UNITED STATES PATENT OFFICE.

FREDRIK OTTESEN, OF PITTSBURG, PENNSYLVANIA, ASSIGNOR TO MESTA MACHINE COMPANY, OF PITTSBURG, PENNSYLVANIA, A CORPORATION OF PENNSYLVANIA.

COMBUSTION-ENGINE.

No. 893,359.

Specification of Letters Patent.

Patented July 14, 1908.

Application filed December 20, 1907. Serial No. 407,400.

To all whom it may concern:

Be it known that I, FREDRIK OTTESEN, a subject of the King of Norway, residing at Pittsburg, Allegheny county, Pennsylvania, 5 have invented a new and useful Improvement in Combustion-Engines, of which the following is a full, clear, and exact description, reference being had to the accompanying drawings, forming part of this specification, in which—

Figure 1 is a vertical section through the inlet gear of a gas engine combustion chamber, and illustrating one form of the invention; and Fig. 2 is a plan view of the main inlet valve.

This invention has relation to combustion engines, and more particularly to inlet valve gear therefor, the objects being to secure a better correlation of operations in the inlet 20 cycle, to insure greater certainty and positiveness in operation, and to provide means whereby the admission of the fuel which forms the basis of combustion may be controlled both as to quality and quantity.

The invention will be best understood by reference to the accompanying drawing, which will now be described, it being premised, however, that various changes may be made therein by those skilled in the art 30 without departing from the spirit and scope of my invention as defined in the appended claims.

The numeral 2 designates the main cylinder of the engine, and 3 is the inlet port therefor. Seated on the cylinder 2 over the inlet port is a cage 4 having formed therein the two annular chambers 5 and 6 separated by a horizontal partition 7.

8 is a gas supply passage communicating 40 with the chamber 5, and 9 is an air-supply passage communicating with the chamber 6. The inner wall of the chambers 5 and 6 is formed by a sleeve or bushing 10 having therein a series of gas admission ports 11, 45 and two sets of air admission ports 12.

13 designates the main inlet valve, which closes the port 3, and it is carried by a rod or stem 14 which passes upwardly through a cap or cover 15, which closes the upper end of the 50 sleeve or bushing 10.

16 is a spring which normally holds the valve 13 seated, the valve being positively opened by means of the levers 17 and 18 actuated by connection 19 with a cam or

eccentric, (not shown) on a rotating part of 55 the engine.

Within the sleeve or bushing 10 and secured to the rod or stem 14 is a mixing valve 20, consisting of a hollow cylinder having a series of ports 21 which are designed to be 60 moved into register with the ports 11, and two series of ports 22, which are designed to be moved into register with the respective ports 12. The valve 20 is rigidly secured to the rod or stem 14 so as to move up and down 65 with the inlet valve 13, and is to be considered as positively operated. The ports in this mixing valve are so cut that the combined area of the gas and air passages is equal to the area of the inlet opening of the 70 valve 13 at any point of the lift, thereby securing a suction pressure through said passages proportioned to the corresponding load.

The gas and air passages 8 and 9 are respectively connected with gas and air supply pipes 23 and 24, a butterfly valve 25 being interposed in the connection between the pipe 23 and the passage 8, and a similar valve 26 being interposed in the connection between the pipe 24 and the passage 9. The 75 stems of the two valves 25 and 26 are connected on the exterior of the inlet passages by an adjustable link 27, which is attached to arms 28 on the respective stems or shafts and rigidly secured thereto. The stem or shaft 80 of the valve 26 also has an arm 29 which is connected by a link rod 30 with a bell crank lever 31 actuated by the governor 32.

The operation is as follows:—The main valve 13, together with the ports 22 of the 90 mixing valve open first, while the exhaust valve (not shown), is still open, thus allowing a rush of fresh air to pass into and through the cylinder, and scavenge it. As soon as the exhaust valve closes, the gas ports 21 on the 95 mixing valve open, and from this point on both gas and air pass through the mixing valve, becoming thoroughly mixed therein before entering the cylinder 2. At the proper time all the valves close and the compression 100 of the mixture takes place.

The invention provides means for obtaining both a quality and quantity regulation of the incoming gas and air. By means of the adjustable link connection 27 the relative 105 angles of the two valves can be varied, and a further variation is possible by a different initial setting of the valves on the stems.

For this purpose, they are adjustably clamped on their stems as indicated at 33 in Fig. 1. In the position shown in the drawing, the gas passage is partially throttled, 5 while the air passage is full open. The mixture is thus weakened giving a quality regulation. Should the load on the engine further decrease, the governor will rapidly increase the throttling of the gas passage, and 10 when this passage is almost closed, the valve 26 in the air passage will commence to throttle. The supply of both gas and air is now throttled, giving a quantity regulation.

The mixing valve 20 is formed with a number 15 of helically directed vanes or interior webs 20^a, which as the valve is moved act to cause a more thorough and intermediate commingling of the gas and air in a manner which will be readily understood. This is an 20 important feature of my invention.

It will be readily seen that the point at 25 which the air supply commences to be throttled may be controlled at will. It will further be noted that by the construction and arrangement of the mixing valve as shown and described, said valve is substantially balanced in its movements, as are also the throttle valves.

It will be obvious that various forms of 30 connections with the governor may be employed for operating the throttle valves, and also that the main inlet and mixing valves may be positively operated by any suitable connection with a moving part of the 35 engine, instead of in the particular manner illustrated. Various other changes may be made in the details of construction and arrangement.

What I claim is:—

1. In a combustion engine, an annular gas 40 chamber having an inlet leading to the cylinder, a reciprocating inlet valve for controlling said passage, and a mixing valve in said chamber working with the inlet valve, said mixing valve having a series of helically directed vanes or webs, together with separate gas and air inlet passages leading into the 45 said chamber at different points; substantially as described.

2. In a combustion engine, an annular gas 50 and air supply chamber, a balanced mixing valve working therein, means for positively operating said valve, a main inlet valve working with the mixing valve, said mixing valve having interior helical vanes or webs, 55 and separate gas and air supply ports leading into said chamber at different points in the travel of the mixing valve; substantially as described.

3. In a combustion engine, a gas and air 60 supply chamber, a reciprocating main inlet valve, a mixing valve arranged to reciprocate with the main inlet valve and having interior helical webs or vanes, and two sets of ports, 65 gas and air supply passages leading into said chamber, independent valves for controlling the gas and air supply, and a governor connection for controlling said valves; substantially as described.

In testimony whereof, I have hereunto set 70 my hand.

FREDRIK OTTESEN.*
